FOLDING MACHINE

Walter J. Beattie, Cohoes, N. Y., assignor to The
Beattie Manufacturing Co., Cohoes, N. Y., a
corporation of New York

Application December 30, 1932, Serial No. 649,609

6 Claims. (Cl. 223—38)

The present invention relates to folding machines intended for folding the edges of collar blanks, and for pressing the folded edges in order that the fold will remain after the blank is removed from the machine.

5 The principal object of the invention is to provide an apparatus which will perform the ordinary operations of an infolding machine, and which will, in addition, produce on the folded edge 10 of the collar blank a number of indicia to facilitate assembly.

Another object of the invention is to provide 15 an apparatus which will infold and mark collar blanks of various sizes.

15 A further object of the invention is to provide an apparatus which may be adapted as an attachment to infolding machines of the types now in use.

In assembling collars, that is, in stitching the 20 collar top to the band, it is convenient to have on the band indicia denoting where the ends of the top should be attached. I have found it expedient to place these marks on the upper edge of the blank near the ends thereof.

25 In stitching the blank carrying the collar top to the shirt collar band, it is also desirable to have indicia on the lower edge of the blank at points which will conform to the shoulder seam of the shirt.

30 In addition, I have ascertained that a similar mark on the lower edge of the blank at the center thereof is advantageous for assembling purposes.

Chalk marks, or marks stitched in the blanks 35 have not proved suitable, and I have found that impressions made while the blank is on the infolding die, are not only adequately permanent, but can also be placed with exactness.

The various features of the apparatus to accomplish these objects will be obvious from the 40 description of one embodiment thereof illustrated in the accompanying drawings, wherein:

Fig. 1 is a top plan view of the machine, showing the die head in its elevated position.

Fig. 2 is a side elevation, showing the die head 45 lowered on to the bed plate.

Fig. 3 is a top plan view of the bed plate.

Fig. 4 is a horizontal sectional view taken on the line 4—4 of Fig. 1.

50 Fig. 5 is a longitudinal vertical sectional view of the bed plate taken along the lines 5—5 of Fig. 3, showing the relation of one edge of the forming die thereto, the die being expanded.

Fig. 6 is a longitudinal vertical sectional view 55 of the bed plate taken along the lines 6—6 of Fig.

3, showing the relation of the other edge of the forming die thereto, the die being expanded.

Fig. 7 is a transverse vertical sectional view of the die head taken on the line 7—7 of Fig. 1, and

Fig. 8 is a transverse vertical sectional view of 5 the die head taken on the line 8—8 of Fig. 4.

Referring more particularly to the drawings, reference character A designates the die head with its forming die 10, which is carried by the arm 11 pivoted to the machine frame at 12. 10 Through the working table 13 of the machine, which is hollow, a heated bed B is adapted to move vertically, said movement being controlled by a suitable foot treadle mechanically connected to bed B through the link 14. Infolding plates C 15 are mounted for lateral movement above heating boxes 15, the latter being secured to the working table 13 of the machine.

When a blank of material is placed on the heated bed, and the forming die lowered thereon, 20 the infolding plates are moved in over the edges of the forming die to infold the edges of the material over the forming die in a manner well known in the art. While the infolding plates are in their inner position, bed B is elevated by the 25 foot treadle to press or crease the folded edges of the material over the forming die.

The structure and operation thus far described is old in the art, it having been described in my prior U. S. Letters Patent No. 972,320, issued October 11, 1910, and in U. S. Letters Patent No. 666,766, issued January 29, 1901, to John Maitland and myself.

Fixed to the upper surface of the bed B is a bed plate 16, having in its upper surface a channel 35 17. As shown in Fig. 3, fixed within the said channel is a plate 18, and adjacent the plate 18 are positioned end to end three plates 19, 20 and 21. The upper surfaces of the said plates are flush with the upper surface of bed plate 16. 40

In the surface of plate 18 are formed a series of recesses or grooves 22 which constitute one element of cooperating embossing dies and provide for co-action with projections on the forming die, as will hereinafter be described. A series 45 of such recesses or grooves, as shown, meet the requirements of adjustability of the apparatus for various collar sizes.

The plate 20, which I term a "size plate" is provided with one recess or groove 23 in its upper surface to constitute one element of a cooperating embossing die and to co-act with a projection on the forming die in a manner hereinafter described. As particularly disclosed in Figs. 3 and 6, the recess or groove 23 is positioned cen- 55

trally of the length of the bed plate 16 by means of an aperture 24 through the size plate 20 which fits over a pin 25 projecting from said bed plate. A screw threaded hole 26 is drilled through the size plate 20 for the connection of a tool to facilitate removal of said plate from the channel 17.

Plates 19 and 21, which I term "end plates", are retained exteriorly of the ends of the size plate 20, and each plate has on its surface a projection 28 which constitutes one element of a co-operating embossing die and provides for cooperation with recesses in the forming die as will be later described.

Referring to Fig. 6, the outer ends of the size plate 20 and the inner ends of the end plates 19 and 21 are rabbeted as shown at 29, and pins 30 carried by the end plates project through apertures 31 in the plate 20 to secure the respective plates together. By reason of such connection, the end plates may easily be removed in order that size plates of various lengths according to the size of collar being folded and marked may be inserted. It will be apparent that the length of the size plate 20 will determine the position of the end plate projections 28.

In Figs. 1 and 4 the forming die 10 is shown as comprising end sections 32 and 34 and central section 33, rigidly carried respectively by forming die section carriers 35, 37 and 36. Sections 32 and 34 have at one end on their under surface projections 38' and 38, respectively, each projection being adapted to cooperate with one of the recesses or grooves 22 in plate 18 when the die is lowered and the bed plate elevated to form indicating marks or impressions on the folded edge of the blank, said marks or impressions denoting points on the blank where the ends of the collar top are to be attached.

The opposite edge of sections 32 and 34 are provided with recesses or slots 39 and 40, respectively, which are adapted to cooperate with projections 28 on the plates 19 and 21, respectively, to form indicating marks or impressions on the folded edge of the collar blank, said marks or impressions designating the points of attachment of the blank to the shirt collar band at the shoulder seams.

Section 33 has in one edge on its under surface a projection 41, which with recess or groove 23 in the size plate 20, constitutes an embossing die to make an indicating mark or impression on the folded edge of the blank to designate the center thereof.

The central section carrier 36 is fixedly mounted to an angle bar 42 by a bolt 43, as shown in Fig. 8. As indicated in Figs. 1 and 7, section carrier 37 is adjustably mounted on angle bar 42, the latter being rigidly secured to a top plate 44 by means of bolts 45. Carrier 37 may be adjusted longitudinally along angle bar 42 and secured thereto by means of bolts 46 passing through slots 47 in the angle bar, and screwing into spaced threaded apertures 48 in carrier 37. This adjustment serves to place projection 38 with reference to a selected recess or groove 22 for the proper collar size, and to likewise place recess 40 with respect to projection 28.

Carrier 35 is adjustably mounted to an angle bar 49 in the same manner as is carrier 37 to angle bar 42, but angle bar 49 is movably attached to top plate 44, this movement being longitudinal of top plate 44, and being controlled by the pressure of a spring 50 which is fastened at its ends to angle bars 49 and 42.

As shown in Fig. 1, a portion of the inner end

surface of angle bar 49 constitutes a cam surface 51, while a portion 52 of one end surface of angle bar 42 also functions as a cam surface. This arrangement of cam surfaces is clearly shown in my prior Patent No. 972,320, granted October 11, 1910.

Referring to Fig. 2, a link 53 has a pivot 54 adjacent pivot 12 and carries at its opposite end a cam 55, said cam cooperating with cam surfaces 51 and 52 to move angle bar 49 carrying forming die section 32 outwardly with respect to angle bar 42 and forming die section 33 when the die head is lowered, spring 50 serving to return angle bar 49 and forming die section 32 to their inner position when the die head is raised and cam 55 is retracted. This contraction of the forming die after the infolding operation serves to facilitate the stripping of the infolded blank from the forming die.

In preparing the machine for operation on the desired size of collar blank, the proper size plate 20 is secured in the bed plate, and the end plates 19 and 21 are secured thereto. The die head is then lowered as in Fig. 2, angle bar 49 being moved to its outer position by cam 55, after which projections 38' and 38 are lined up above the selected recesses or grooves 22, (as shown in Fig. 5), by adjusting carriers 35 and 37 along angle bars 49 and 42, respectively, and securing the carriers by bolts 46. Obviously, recesses 39 and 40 will be likewise aligned by this adjustment above projections 28, as shown in Fig. 6.

In operation, the die head is raised, a blank of material is centered on the bed plate, and the die head is lowered, placing the forming die centrally of the blank. By suitable mechanism well known in the art, the infolding plates are moved into fold the edges of the material over the edges of the forming die, and while the infolding plates are in their inward position, heated bed B carrying bed plate 16 is elevated by a foot treadle to press or crease the infolded edges of the blank between the bed plate and the infolding plates, and over the edges of the forming die, the complementary projections and recesses on the forming die and bed plate serving to emboss the folded edge of the material with properly spaced indicating impressions.

Obviously, the details of the preferred embodiment described may be modified materially without departing from the spirit of the invention, particularly in regard to the number of forming die sections and the disposition of the complementary projections and recesses on the forming die and bed plate. For instance, the forming die could be divided into more than three sections to obtain greater precision in the adjustability of said sections with their projections or recesses and the complementary projections or recesses in the bed plate. Furthermore, a reversal of the arrangement of the projections on and the recesses in the forming die and bed plate is contemplated, or, the projections might all be on the forming die and the recesses all in the bed plate, or vice versa.

I claim:

1. In a machine of the class described, a material supporting bed provided with a channel, plates having recesses and projections in said channel, forming dies provided with projections and recesses, and infolders adapted to infold a blank of material, said recesses and projections, respectively, being complementary and adapted to produce a plurality of indicating marks on the infolded blank of material.

2. In a machine of the class described, a material supporting bed provided with a channel, plates having recesses and projections in said channel, forming dies provided with projections and recesses, and infolders adapted to infold a blank of material, said recesses and projections, respectively, being complementary and adapted to produce a plurality of indicating marks on the infolded blank of material, and some of said plates and said forming dies being adjustable to vary the positions of the indicating marks.

3. In a machine of the class described, a material supporting bed provided with a channel, a fixed plate having recesses and adjustable plates having projections in said channel, adjustable forming dies provided with projections and recesses, and infolders adapted to infold a blank of material, said recesses and projections, respectively, being selectively complementary to produce a plurality of indicating marks on infolded blanks of material of varying lengths.

4. In a machine of the class described, a material supporting bed provided with a channel, a fixed plate having a series of recesses adjacent each end, and three plates comprising a central plate having a recess and end plates having projections rabbeted together in said channel, three forming dies comprising a fixed central die having a projection, and adjustable end dies each having a projection and a recess, and

infolders adapted to infold a blank of material, said recesses and projections, respectively, being selectively complementary to produce a plurality of indicating marks on the infolded blanks of material of varying lengths.

5. In a machine of the class described, a material supporting bed provided with a channel, a fixed plate having a series of recesses adjacent each end and an adjustable plate structure comprising a middle plate having a central recess and a pair of slidable plates provided with projections in said channel, adjustable forming dies provided with a plurality of projections and a plurality of recesses, and infolders adapted to infold a blank of material, said recesses and projections, respectively, being selectively complementary to produce a plurality of indicating marks on infolded blanks of material of varying lengths.

6. In a machine of the character described comprising a material supporting bed member, a forming die, infolding means, said bed and forming die and infolding means operable to infold a blank of material, a channel in said bed, a size plate fixed in said channel, a pair of end plates in said channel one on each end of said size plate, and complementary means associated with said forming die and said plates for producing indicating impressions in the infolded blank along the edge thereof.

WALTER J. BEATTIE.
